GASEOUS ELECTRIC DISCHARGE LAMP
DEVICEEduard G. Dorgelo, Eindhoven, Netherlands, as-
signer to General Electric Company, a corpo-
ration of New YorkApplication July 16, 1935, Serial No. 31,702
In Germany July 26, 1934

2 Claims. (Cl. 176—124)

The present invention relates to gaseous electric discharge lamp devices generally and more particularly the invention relates to illuminating systems incorporating such devices.

5 Illuminating systems comprising a plurality of gaseous electric discharge lamps and a plurality of transformers in which the transformer primaries are connected in series are useful for lighting large outdoor or indoor areas, such as roads, 10 airports, athletic fields, piers or armories. I have observed that high voltage conditions frequently exist between the current supply leads of the discharge lamps; when said leads are closely spaced flash-overs occur which are destructive 15 of the insulation on or between the leads. For example, in an illuminating system for a highway in which the transformer primaries are connected in series to a constant current transformer by a cable of approximately 8 kilometers in 20 length voltage surges of several thousand volts frequently occur between the current supply leads at the lamp bases which are destructive of such bases.

The object of the present invention is to provide 25 an illuminating system of the above type in which destructive voltage surges do not occur. Still further objects and advantages attaching to the device and to its use and operation will be apparent to those skilled in the art from the following particular description.

I have discovered that destruction voltage surges are avoided in such circuits when a choke coil which is highly saturated during the operation of the system (induction preferably larger 35 than fifteen thousand gauss) is connected in series with the transformer primaries. Preferably the choke coil is connected into the transformer circuit at a part thereof remote from the current source.

40 In the drawing accompanying and forming part of this specification an illuminating system embodying the invention is shown schematically.

Referring to the drawing the illuminating system comprises a plurality of gaseous electric discharge lamp devices 1. Each of said lamp devices 1 comprises a tubular U-shaped container having thermionic electrodes sealed therein at each end thereof and a gaseous atmosphere therein comprising rare gas, such as neon, or a mixture of a starting gas and a metal vapor, such as a mixture of argon, neon and sodium vapor. Each of the thermionic electrodes comprises a heater filament, such as a tungsten filament in operative relation to a body of electron emitting 50 material, such as barium oxide. When desired

the filament has a coating of the electron emitting material thereon. Said electrodes are of the directly heated type, that is, the voltage drop thereat and the discharge current serves to raise them to and maintain them at an electron emitting, discharge supporting temperature.

5 Each of said lamp devices 1 is connected to the secondary 2 of a transformer 3. The primaries 4 of said transformers 3 are connected in series across the terminals 6 of a current source by the leads 5. The current source is a constant current transformer, that is, a transformer having a movable secondary coil whereby the current supplied by the secondary is substantially constant. The choke-coil 7 is connected between 10 the supply leads 5 at a part of the current supply circuit remote from the current source. The choke-coil 7 is highly saturated during the operation of the system, so that the operation takes place above the knee of the curve which shows 15 the induction as a function of the current. The induction is seventeen thousand gauss, when desired. Destructive voltage surges do not occur in the above described circuit and the lamps have 20 a long useful operating life.

25 What I claim as new and desire to secure by Letters Patent of the United States is:—

1. An illuminating system comprising in combination an alternating current source, a plurality of gaseous electric discharge lamps, a plurality 30 of transformers therefor, the primaries of said transformers being connected in series across the terminals of said alternating current source, each of said lamps being connected across the secondary of one of said transformers and a 35 choke-coil connected in series with said transformer primaries, said choke-coil being saturated during the operation of said lamps to prevent deleterious voltage surges across the terminals of 40 said lamps.

2. An illuminating system comprising in combination an alternating current source, a plurality of gaseous electric discharge lamps, a plurality of transformers therefor, the primaries of said 45 transformers being connected in series across the terminals of said alternating current source, each of said lamps being connected across the secondary of one of said transformers and a choke-coil connected in series with said transformer primaries at a part of said system remote from 50 said current source, said choke-coil being saturated during the operation of said lamps to prevent deleterious voltage surges across the terminals of said lamps.
